UNITED STATES PATENT OFFICE.

CHARLES HAMILTON MINSHALL, OF LONDON, ENGLAND.

DESIGN FOR A GOLF PUTTING DEVICE.

45,306.

Specification for Design.

Patented Feb. 24, 1914.

Application filed December 10, 1912. Serial No. 736,029. Term of patent 14 years.

To all whom it may concern:

Be it known that I, CHARLES HAMILTON MINSHALL, a subject of His Majesty the King of Great Britain, whose post-office address is 70 Gracechurch street, in the city and county of London, England, have invented a new, original, and ornamental Design for Golf Putting Devices, of which the following is a specification, reference being had to the accompanying drawing, forming part thereof.

In the accompanying drawing, illustrating my new design,—Figure 1, is a plan view thereof, and Fig. 2, is an elevation thereof.

I claim:—

The ornamental design for a golf “putting” device, as shown.

CHARLES HAMILTON MINSHALL.
